UNITED STATES PATENT OFFICE.

LEE A. MEDCALF, OF FAIRGROVE, MICHIGAN.

SORTING MACHINE.

Application filed May 3, 1926. Serial No. 106,247.

This invention relates to seed sorting machines and particularly to a machine for separating good beans from the culs, split and otherwise imperfect product.

- 5 One object of the invention is to design a simple and efficient sorting machine which can be built in units so that any number of units may be added to provide the desired capacity.
- 10 Another object is to design a flat revolving table or disc machine, and provide means for separating the product and guiding it into separate receptacles.

15 A further object is to provide a sectional roller and mount it on the face of the disc for separating the perfect from the imperfect product.

20 A further object still is to design a new and novel sectional scraper which will closely hug the face of the disc and accommodate itself to an unevenness of surface.

25 With the above and other objects in view, the present invention consists in the combination and arrangement of parts, hereinafter more fully described, illustrated in the accompanying drawings, and particularly pointed out in the appended claims, it being understood that changes may be made in the form, size, proportion and minor details of 30 construction without departing from the spirit or sacrificing any of the advantages of the invention.

In the drawings,

35 Fig. 1 is a top plan of a revolving disc machine showing the sectional roller and scrapers in place thereon.

Fig. 2 is a fragmentary part sectional view, the outer frame being omitted.

40 Fig. 3 is a fragmentary top plan of one of the sectional scrapers.

Fig. 4 is a fragmentary side view.

45 Fig. 5 is a transverse sectional view, the dotted lines showing one of the sections raised.

Fig. 6 is an enlarged fragmentary side view of the sectional roller.

Fig. 7 is an end view thereof.

50 Fig. 8 is a fragmentary top plan view illustrating the manner of connecting one of the braces to one of the sectional scrapers.

Fig. 9 is an edge view thereof.

Fig. 10 is a fragmentary isometric view showing the sectional roller and bearing.

Fig. 11 is a fragmentary side view of the seed agitating member and

55 Fig. 12 is a transverse sectional view thereof.

Fig. 13 is a part sectional view of the main feed spout.

Referring now particularly to the drawing, the machine comprises a supporting frame 5 having a bearing 5^a cast integral therewith and in which a hollow shaft 6 is journaled, a bevel gear 7 being secured to the shaft intermediate its length, and is adapted to be driven by a bevel pinion 8 mounted on the shaft 9, and which is connected to a suitable source of power (not shown), a cone shaped member 10 being secured to the upper end of the shaft 6, and is provided with 70 a flange 10^a on which a flat disc or table 11 is mounted and secured for rotation therewith, and which is practically identical with the construction shown in Patent #1,479,082, granted to me under date of 75 January 1st, 1924, and this application is therefore primarily directed to the sectional roller and scrapers, and the mounting thereof.

The table or disc proper is perfectly flat, 80 and is slightly tilted as shown in Fig. 2, of the drawing, a centrally disposed opening 12 being provided which communicates with the hollow shaft 6 as shown.

85 A sectional scraper 13 rests on the face of the disc in the position as shown, and is preferably formed of metal, being channel shaped and is adapted to receive a plurality of short block members 14 therein, and which are placed in abutting relation. The ends of 90 the channel shaped member extend beyond the disc, and are secured to a frame 15 which surrounds the machine, by means of bolts 16. A second scraper 17 is spaced from the scraper 13, the block members extending only 95 to the point 18, the channel frame portion also extending to the frame and in the same manner, and bolts 19 are provided for holding it in proper position, the portion of the channel frame in which there are no blocks 100 being of sufficient height from the face of the disc to allow the product being sorted to pass thereunder.

An identically similar scraper 20 is positioned on the low side of the disc, the scraper 105 blocks extending to the point 21, the metal

frame being secured to the outer frame 15 identically the same as the other scrapers.

A curved sheet metal member or section 22 is secured to the members 17 and 20 in the 5 position as shown, and acts as a guide to prevent good product from rolling past the scraper 20 and off the lower edge of the disc, guiding it in the direction as indicated by the numerous arrows, thence striking the 10 scraper 20 and being carried upward to the sectional roller 23 in a manner to be presently described.

A transversely disposed brace member 24 is secured to the scraper member 17 and 20 15 respectively, bolts 25 being anchored in and projecting from said members, and extending through suitable openings provided in the brace, bearings 26 and 27 being secured to said brace 24 and 24^a respectively, and are 20 formed as clearly shown in Fig. 9, of the drawing, having an open socket 28 in which a shaft 29 is journaled.

The roller 23 is mounted on the shaft 29 and is formed of a plurality of sections 30, 25 spaced from each other by means of a thin metal washer (not shown), the opening 31 which is provided in said sections being considerably larger than the diameter of the shaft to permit the sections to raise or lower 30 with respect to the shaft and independently of each other, as when one section rolls over a cracked or very irregular shaped beam or flat surface or a piece of foreign matter.

An agitating or turning member 32 is 35 spaced from the sectional roller and is rigidly secured to the brace 24 and the brace 24^a respectively, pins 33 being provided in said member in staggered relation, and serve to turn the beams as they are carried around 40 on the disc.

A feed hopper 34 is provided directly adjacent the disc and into which the product to be sorted is dumped and this is provided with a spout 35 having a slotted opening 36 45 therein, and into which the edge of the revolving disc projects, a lip 37 being provided at the lower edge of the slotted opening, and prevents the beams from wedging beneath the disc. The beams are prevented 50 from rolling off the edge of the disc by a thin circular band of metal 38 which extends partially around the disc and is secured to the members 17 and 13 respectively.

In practise the revolving disc carries the 55 beans (as they are fed from the spout) up against the scraper 13, the regular shaped perfect product rolling down (due to the angle of inclination of the disc) towards the low side thereof, while the foreign matter, cracked and very imperfect product is carried around on the outer edge of the disc, outside of the guard 22 being carried against the back side of the scraper 20, and are then forced off the disc and into the hopper 39 60 as above described.

The perfect smooth skinned product together with the smooth irregular shaped and shriveled skinned beans roll inside of the guard 22 and against the front edge of the scraper 20, thence are carried in under 70 the agitating member 31 which rolls the product, thence being carried to the sectional roller, the round curvature of the roller sections obviously will not grip a perfectly smooth round object, consequently the good 75 product will not pass thereunder but will be forced off the disc and into the mouth of the spout 40, the cracked, shriveled and otherwise imperfect product will be caught by the roller sections which will allow them 80 to pass thereunder, being carried against the edge of the scraper 17, and are forced towards the center of the disc and into the opening 12 which communicates with the hollow shaft from which they are discharged 85 into a suitable receptacle 41 provided beneath the frame.

The roller 23 can be easily removed by merely lifting it from the bearings and can be made up of any desired material to suit the seed being sorted, and I find that rubber is the most suitable for sorting beans, but when sorting peas, etc., I find that felt is found to be most satisfactory for catching the thistle blows which are then removed by 95 brushing the rolls.

From the foregoing description it will be obvious that I have perfected a very simple, economical and substantial sorting machine.

What I claim is:—

1. A frame, a sorting device comprising a flat disc, a roller mounted on the frame, and comprising a shaft having a plurality of individual sections loosely mounted thereon and free to move in any direction and riding on said disc. 105

2. A frame, a sorting device comprising a flat revolving disc, a roller mounted on the frame, and comprising a plurality of individual sections movable in any direction and with relation to each other and adapted to ride on said disc. 110

3. A frame, a sorting device comprising a flat revolving disc, scrapers mounted on the frame, in spaced relation, and a roller formed of individual sections also mounted thereon and riding on said disc. 115

4. A frame, a sorting device comprising a tilted flat revolving disc, sectional scrapers mounted on the frame in spaced relation, and a sectional roller journaled on the scrapers and riding on said disc. 120

5. A main frame, a sorting device comprising a flat revolving disc, scrapers mounted on the frame, each comprising a frame having a plurality of blocks loosely mounted for vertical movement therein, and a sectional roller journaled on the main frame and comprising a plurality of individual sections riding on said disc. 125 130

6. In a sorting device, the combination with a flat revolving surface, of a frame, a sectional roller mounted thereon, the sections being movable in any direction and with relation to each other.
7. In a sorting device, the combination with a flat revolving disc, of a frame, a sectional roller mounted thereon, and comprising a shaft, a plurality of individual sections mounted thereon, and a centrally disposed opening in each section of greater diameter than the diameters of the shaft to
8. In a sorting device, the combination with a flat revolving disc, a frame, a sectional roller mounted thereon, scrapers mounted on the disc in spaced relation, and comprising a channel shaped frame, and a plurality of blocks loosely mounted in said frame in abutting relation.

In testimony whereof I hereunto affix my signature.

LEE A. MEDCALF.
